DESIGN FOR A SERVICE RECORD SHIELD

Arthur C. Werback, Garden City, N. Y.

Application October 11, 1944, Serial No. 115,710

Term of patent 3½ years

(Cl. D29—23)

To all whom it may concern:

Be it known that Arthur C. Werback, a citizen of the United States of America, residing at Garden City, Long Island, in the county of Nassau and State of New York, has invented a new, original, and ornamental Design for a Service Record Shield, of which the following is a specification, reference being had to the accompanying drawings, forming part thereof.

I claim:

The ornamental design for a service record shield, as shown.

ARTHUR C. WERBACK.
